TELEVISION ANTENNA

John Hlivjak, Chicago, Ill., assignor to True
Tronics, Inc., Chicago, Ill., a corporation of
Illinois

Application October 23, 1952, Serial No. 316,401

8 Claims. (Cl. 250—33)

1

This invention relates to antennas and, more specifically, to antennas which are particularly well adapted for use with both V. H. F. and U. H. F. television broadcast band receivers and FM broadcast band receivers.

Various types of antennas, both for indoor and outdoor use, have heretofore been known in the art. However, such antennas as have been heretofore known in the art have had several inherent disadvantages such as, for example, being large and bulky in size; being difficult to manufacture and assemble; and being inefficient in operation. It is a primary object of my invention to overcome such disadvantages and to afford a novel efficient antenna which is relatively small in size, may be readily and economically manufactured commercially, and may be quickly and easily assembled.

Another important object of my invention is to provide an antenna of the aforementioned type which affords an especially effective and efficient indoor antenna but which, if desired, may also be used outdoors to afford a novel, effective outdoor antenna.

Another object of my invention is to afford a novel antenna of the aforementioned type which, though relatively small in size, has improved gain characteristics.

A further object is to afford an antenna which is efficient in operation without requiring the antenna to be mounted high in the air.

Another object of my invention is to provide a novel antenna which, in most instances, does not require change of location when the receiving channel is changed in order to afford proper reception.

Many of the antennas heretofore known in the art, and especially the indoor antennas, are highly sensitive to the gain or interference afforded by the body of a person when that person is maneuvering the antenna, or, in some instances, even when the person is standing in relatively close proximity to the antenna, such as, for example, when the person is tuning the receiver. This makes it difficult to properly tune the receiver for good reception because of the different receiving characteristics encountered when the person is in close proximity to the antenna and when he is at the normal, and considerably greater, distance therefrom for viewing the program.

It is an object of my invention to afford an antenna which is relatively non-sensitive to a person maneuvering the same or standing in close proximity thereto.

Another object of my invention is to afford a novel antenna of the aforementioned type which is less susceptible to electrical and automotive disturbances than antennas heretofore known in the art.

2

A further object of my invention is to afford a novel dipole antenna having two end portions on which equalization of the wave lengths is improved.

5 A further object is to afford a novel antenna of the aforementioned type which embodies a novel auxiliary antenna which affords improved holding of the wave length and adds to the gain of the antenna.

10 Another object of my invention is to provide a novel antenna which embodies an auxiliary antenna which is effective and affords improved performance in the so-called "standard" very high frequency wave lengths and also in the ultra-high frequency wave lengths.

15 Yet another object of my invention is to provide an antenna of the aforementioned type which embodies a main dipole antenna and an auxiliary antenna constituted and arranged in a novel and expeditious manner.

An object ancillary to the foregoing is to afford a novel antenna embodying a novel auxiliary antenna disposed in a plane extending between the opposite longitudinal sides of a folded dipole antenna.

20 Another object of my invention is to afford a novel antenna of the aforementioned type which embodies, as a part thereof, a novel auxiliary antenna embodying two bars disposed in substantially end-to-end relation with the adjacent ends disposed in spaced relation to each other and the outer ends thereof electrically interconnected by a conductor of relatively high resistance.

25 A further object of my invention is to afford a folded dipole antenna having slideable sections and embodying an auxiliary antenna disposed between the bars of the trombone in a manner to effectively capture the wave length of the transmitting station.

30 35 Other and further objects of the present invention will be apparent from the following description and claims and are illustrated in the accompanying drawings which, by way of illustration, show a preferred embodiment of the present invention and the principles thereof and what I now consider to be the best mode in which I have contemplated applying these principles. Other embodiments of the invention embodying the same or equivalent principles may be used and structural changes may be made as desired by those skilled in the art without departing from the present invention and the pur-

40 45 50 view of the appended claims.

55 In the drawings:

Fig. 1 is a front elevational view of an antenna embodying the principles of my invention;

Fig. 2 is a top plan view of the antenna shown in Fig. 1;

Fig. 3 is a rear elevational view of the antenna shown in Fig. 1;

Fig. 4 is a detail sectional view taken substantially along the line 4—4 in Fig. 3;

Fig. 5 is a detail elevational view of a portion of the antenna shown in Fig. 3;

Fig. 6 is a detail sectional view taken substantially along the line 6—6 in Fig. 5;

Fig. 7 is a detail sectional view taken substantially along the line 7—7 in Fig. 5;

Fig. 8 is a detail sectional view taken substantially along the line 8—8 in Fig. 5;

Fig. 9 is a detail sectional view taken substantially along the line 9—9 in Fig. 5; and

Fig. 10 is a detail sectional view taken substantially along the line 10—10 in Fig. 5;

To illustrate the principles of my invention, an antenna 20 comprising a preferred embodiment of my invention, is shown in the drawings. The antenna 20 comprises, in general a dipole folded antenna 22 and an auxiliary antenna 24 mounted on a stand 26 and constituted and arranged in a novel and expeditious manner to afford a novel, and highly effective unitary antenna for receiving television broadcasts as will be discussed in greater detail hereinafter.

The dipole folded antenna 22 embodies two pairs of bars 31 and 32, and 33 and 34, respectively, in the form of hollow tubes mounted on a terminal block or mounting block 35, and projecting outwardly therefrom in opposite directions. Two substantially U-shaped slides 36 and 37, each having two spaced, substantially parallel legs 36a and 36b, and 37a and 37b, respectively, are mounted in the two pairs of tubes 31—34 with the legs 36a, 36b, 37a and 37b mounted in the tubes 31, 32, 33 and 34, respectively.

The mounting block 35 may be made of any suitable dielectric material such as, for example, porcelain or wood and has a front face 35a and a rear face 35b, Figs. 1 and 3. Three substantially parallel grooves 41, 42 and 43, Figs. 5 and 6, are formed in the rear face 35b of the mounting block 35 and are normally disposed in substantially horizontal position, the groove 41 being formed in the upper end portion of the mounting block 35, the groove 43 being formed in the lower end portion of the mounting block 35, and the groove 42 being formed in the mounting block 35 midway between the grooves 41 and 43.

The bars or tubes 31 and 33 are mounted in the groove 41 with the respective inner terminal end portions 45 and 46 thereof terminating in spaced relation to each other, Fig. 5, and with the respective outer terminal end portions 48 and 49 thereof projecting in opposite directions substantially horizontally outwardly from the mounting block 35. The bars 31 and 33 are releasably secured in operative position in the groove 41 by bolts 51 and 52, respectively, and nuts 53 and 54, the bolts 51 and 52 extending through the mounting block 35 and the respective inner end portions of the bars 31 and 33, Figs. 5 and 8.

The bars 32 and 34 are similarly mounted in the groove 43 with the respective inner terminal end portions 56 and 57 thereof disposed in spaced relations to each other and the respective outer terminal end portions 58 and 59 thereof projecting in opposite directions outwardly from the mounting block 35. The bars 32 and 34 are releasably secured in the groove 43 by nuts 61 and 62 mounted on bolts 63 and 64 which

project through the mounting block 35 and the inner end portions 56 and 57 of the bars 32 and 34, respectively.

The tubes 31—34 may be formed of any suitable electrically conductive material, such as, for example, aluminum and the slides or trombones 36 and 37 are formed of suitable material such as, for example, aluminum bar stock. The legs 36a, 36b, 37a and 37b of the slides 36 and 37 are of such diameter that they fit into the respective tubes 31—34 with a snug sliding fit so that good electrical contact is afforded between each leg 36a, 36b, 37a and 37b and the respective tube 31—34 into which it is fitted.

The auxiliary antenna 24 embodies two elongated bars 71 and 72, Figs. 1 and 2, made of any suitable material such as, for example, aluminum tubing mounted in the groove 42 in the mounting block 35 with the inner terminal end portions 74 and 75 thereof, respectively, disposed in spaced relation to each other, Fig. 5, and the outer terminal end portions 71 and 78 of the bars 71 and 72, respectively, projecting outwardly in substantially opposite directions from the mounting block 35. Like the bars 31—34, the bars 71 and 72 are releasably secured in the mounting block 35 by nuts and bolts for quick and easy assembly and disassembly, bolts 82 and 83 extending through the mounting block 35 and the respective inner end portions 74 and 75 of the bars 71 and 72 and having nuts 81 and 82 mounted thereon.

A tension coil spring 85, Figs. 2 and 3, having hooks 86 and 87 at the opposite ends thereof, is normally mounted in tension between the bars 71 and 72, the hook 86 being hooked into the open outer terminal end 71 of the bar 71, and the hook 87 being hooked into the open outer terminal end 78 of the bar 72. The spring 85, which forms a part of the auxiliary antenna 24, is of particular importance in my novel antenna to which it is used in the reception of broadcasts transmitted on ultra-high frequency wave lengths. It not only affords a greater horizontal spread for the reflector antenna which is of importance in the reception of U. H. F. waves but, of course, affords a greater total antenna length and surface. In addition, the spring 85, being constructed of coiled relatively thin wire, affords a relatively long total length of wire of relatively high resistance which forms the only electrical connection between the two sides L and R of the antenna 20.

It will be remembered that the spring 85 is of particular importance when the antenna 20 is used for receiving U. H. F. wave lengths. However, although under certain conditions when my novel antenna 20 is used in the reception of V. H. F. wave lengths the spring 85 may be removed from the bars 71 and 72 and the antenna 20 successfully used without the spring 85 such as, for example, in areas where the signal to be received is what may be called "average," that is, neither weak nor strong, the spring 85 does improve the reception obtained with my novel antenna 20 of V. H. F. wave lengths, especially in areas of strong signals and in the fringe areas where the signal is weak. In the areas where the signal is strong the spring 85 prevents the "flooding" of the antenna heretofore common with antennas known in the art, and in the fringe areas where the signal is weak the spring affords an effective additional antenna surface which is of assistance in "pulling in" the signal.

The inner end portions 45 and 74 of the bars

31 and 71, respectively, are electrically connected by means of a conductor of any suitable material, such as, for example, a strip of copper sheet 91, Figs. 5 and 6, mounted on the bolts 51 and 82 and releasably secured thereto by means of the nuts 53 and 80, respectively. Similarly, the inner end portions 46 and 75 of the bars 33 and 72 are electrically connected by means of a conductor such as a strip of copper sheet material 92, Figs. 5 and 7, mounted on the bolts 52 and 83 and held thereon by the nuts 54 and 81, respectively.

Two lead wires 94 and 95, Figs. 1, 3 and 5, are mounted on the bolts 63 and 64, respectively, and are held in good electrical connection with the inner end portions 56 and 57 of the bars 32 and 34, respectively, by the nuts 61 and 62. The lead wires 94 and 95 afford the conductors by means of which the antenna 20 may be connected to the antenna terminal posts of the television receiver with which it is to be used such as, for example, the terminal posts 97 and 98 on a television receiver 99, a corner of which receiver is shown in Fig. 1.

The stand 26 of the antenna shown in the drawing embodies a supporting base 101, Figs. 1, 2, and 3 and 4, having an upwardly opening, substantially rectangularly shaped pocket 102 formed therein. An L-shaped mast 104 of substantially rectangularly shaped cross section, and having a normally vertically disposed leg 105 and a horizontally disposed leg 106, Figs. 1, 4 and 6, is mounted on the supporting base 101 with the lower end portion of the leg 105 disposed in relatively close fitting relation in the pocket 102. The horizontal leg 106 of the mast 104 is bifurcated having an elongated slot 108 formed therein which extends inwardly from the outer terminal end of the leg 106. Near the outer terminal end portion thereof, the slot 108 is enlarged to afford a substantially round socket 109 therein, Fig. 9, and from the socket 109 to the external end of the leg 106, the slot 108 flares outwardly to afford a guide passageway 110.

A mounting bracket 112, Figs. 5, 6 and 10, comprising two substantially L-shaped bracket plates 113 and 114 having substantially parallel legs 113a and 114a and two outwardly diverging legs 113b and 114b, respectively, are mounted in a recess 116 formed in the central portion of the rear face 75b of the mounting block 35, Figs. 5 and 6, and is held in position therein by bolts 118 and nuts 119, the bolts extending through the mounting block 35 and the legs 113b and 114b in position to hold plates 113a and 114a of the bracket plates 113 and 114 in substantially parallel spaced relation to each other. A roller 121 is mounted between the legs 113a and 114a of the bracket plates 113 and 114 and is held in position therein by a rivet 123 extending through the legs 113a and 114a, Figs. 6 and 10.

In mounting the mounting block 35 on the mast 104, the leg 106 of the mast 104 may be slid into position between the legs 113a and 114a of the bracket plates 113 and 114, and the roller 121 may be moved inwardly through the guideway 110 into the socket 109, which is complementary in shape thereto and wherein the roller 121 is firmly but releasably clamped or gripped between the bifurcations of the leg 106. The lower end of the vertical leg 105 of the mast 104 may be then inserted in the pocket 102 in the supporting base 101 to complete the assembly shown in Figs. 1, 2 and 3.

Thus it will be seen that my novel antenna

may be readily shipped in a partially assembled condition wherein it is separated into three units, the dipole folded antenna 22, the auxiliary antenna 24, and the mounting block 35 forming one unit, the mast 104 forming another unit, and the supporting base 101 forming another unit. The antenna may be quickly and easily assembled from such partially assembled condition by slipping the leg 106 of the mast 104 into position in the bracket 112 and then inserting the leg 105 of the mast 104 into the pocket 102 of the supporting base 104. Likewise, the antenna 20 may be quickly and easily disassembled into the aforementioned partially assembled condition by merely pulling the mast 104 out of the supporting base 101 and then pulling the mast 104 out of the bracket 112.

If desired, of course, the slides 36 and 37 may be removed from the bars 31-34, and the bars 31-34 and 71 and 72 may be readily removed from the mounting block 35, and the antenna 20 may be packed and shipped in this more completely disassembled condition. However, the partially disassembled antenna affords a compact shipping package and will be found to be normally suitable for shipment of my novel antenna.

As is best seen in Fig. 2, the bars 71 and 72 of the auxiliary antenna 24 each project substantially horizontally rearwardly at an acute angle from the dipole folded antenna 22. Such construction, it has been found, results in better absorption of the wave lengths, and affords better performance than if the bars 71 and 72 are disposed in the same vertical plane as the bars 31-34.

Theoretically, it may appear that best performance would be afforded, at least in the reception of V. H. F. broadcasts, with the bars 71 and 72 disposed in the same vertical plane as the bars 31-34. However, I have found that for practical purposes an included angle of from ten degrees to thirty degrees should be maintained between the bars 71 and 72 and the antenna 22. If the included angle between the bars 71 and 72 and the antenna 22 is permitted to become less than ten degrees undesirable operating conditions may be obtained and if the angle is permitted to become greater than thirty degrees too weak a signal is afforded. For reception of V. H. F. broadcasts I prefer to use an included angle between the bars 71 and 72 and the antenna 22 of ten degrees.

As is best seen in Figs. 5 and 10, the inner terminal end portions 74 and 75 of the bars 71 and 72 are flattened to afford a firm practical support for the remaining portions of the respective bars 71 and 72 which project therefrom at an angle.

I have found that for receiving present-day television broadcasts on standard V. H. F. wave lengths and for receiving U. H. F., I prefer, for practical purposes, to construct the antenna 20 for use as an indoor antenna as follows:

(1) The bars 31-34, 71 and 72 made from aluminum tubing eight and three-quarter inches in length and having an outside diameter of three-eighths of an inch and a wall thickness of thirty-five thousandths of an inch, with the outer end portion of the bars 31-34 rolled to decrease the inside diameter thereof to an extent where a bar having an outside diameter of one-quarter of an inch may be received with a snug sliding fit;

(2) The slides 36 and 37 made from round aluminum bar stock having a one-quarter inch outside diameter, each trombone having an over-

all length from closed end to open end of nine and five-eighths inches and the closed end to be rounded on a two and one-quarter inch inside diameter;

(3) The mounting block 35 made from porcelain or other suitable dielectric material and having a length of three and five-eighths inches, a width of two and one-quarter inches, and a thickness of one inch.

(4) The bars 71 and 72 to be mounted in the block midway between the bars 31 and 33 and the bars 32 and 34;

(5) The spring 85 made from spring steel and comprising a closely wound spring having an unexpanded length of ten inches from the outside of the hooks at each end, and having an inside diameter of one hundred and thirty-two thousandths of an inch and an outside diameter of one hundred and fifty-two thousandths of an inch; and

(6) The stand 26 having an overall height of substantially seven and one-half inches.

Such construction it will be seen affords a relatively small, compact antenna which may be readily packed for shipment in a relatively small package, and which antenna I have found provides improved performance over antennae heretofore known in the art which were considerably larger.

It will be appreciated that variations may be made from the above set forth dimensions without departing from the purview of my invention. However, for the reception of television broadcasts on V. H. F. and U. H. F. wave lengths the construction of my novel antenna would not substantially exceed the following limits:

(1) The bars 31—34, 71, and 72 should not be shorter than five inches, nor longer than twenty-eight inches; the outside diameters thereof should not be substantially less than one-quarter of an inch and not substantially more than one inch; and the thickness of the walls thereof should not be substantially less than twenty-eight thousandths of an inch and not substantially more than thirty-eight thousandths of an inch;

(2) The slides 36 and 37 should not be substantially shorter than three inches in over-all length between the closed and open ends thereof nor substantially longer than thirty-three inches, and, of course, should be of proper diameter to fit snugly into the bars 31—34;

(3) The distance between the outer surfaces of the bars 71 and 72 and the adjacent outer surfaces of the bars 31—34 should not be less than one-half an inch and not more than three inches; and

(4) The dimensions of the tubes 31—34, 71 and 72 should always be equal within plus or minus one-eighth of an inch.

I have found that if the length of the bars 31—34, 71, 72, 36 and 37 substantially exceed the aforementioned limits in length too strong a signal results, and if the lengths are substantially less than the aforementioned limits too weak a signal results.

Likewise, I have found that if the space between the outer surface of the bars 71 and 72 and the adjacent surfaces of the bars 31—34 is substantially less than one-half inch too strong a signal results, and if the space is substantially more than three inches too weak a signal results.

From the foregoing it will be seen that with an antenna constructed in accordance with my invention, a novel antenna is afforded which has a

left side L and a right side R when viewed from the front, as seen in Fig. 1, and wherein the left side L embodies the bars 31, 32, and 71, the slide 36, and the conductor 91, and the right side R embodies substantially identical parts, namely, the bars 33, 34 and 72, the slide 37, and the conductor 92. Thus, the antenna 20 comprises a substantially completely split antenna, the only continuity between the left side L and the right side R being the spring 85 which, being of relatively thin, tightly coiled wire, has a relatively high resistance.

Such construction affords improved performance both in the reception of V. H. F. wave lengths and in the reception of U. H. F. Thus, for example, in areas where the signal is strong, and "flooding" of antennae heretofore known in the art would normally result, the construction of my novel antenna is such that flooding thereof does not result, one principal reason being believed to be because of the absorbing effect of the spring 85.

Also, the spring 85 is of importance in affording the improved characteristics of my novel antenna in the reception of U. H. F., my novel antenna having a higher gain because the spring coils afford a higher gain area.

As is well known, the impedance of a folded dipole antenna is approximately three hundred ohms, and with the antenna constructed in accordance with the principles of my invention it will be seen that this is divided substantially equally between the right side R and the left side L, the two sides of my novel antenna being substantially separated from each other, only being connected by the spring 85 which embodies relatively great wave length absorbing or holding characteristics, so that current flow through the lead wires 94 and 95 are, under normal operating conditions, substantially equal.

It will be understood, of course, that the slides 36 and 37 may be slid longitudinally inwardly and outwardly relative to the bars 31—34 to thereby adjust the antenna 20 for the reception of different strength signals, and the like.

From the foregoing it will be seen that I have afforded a novel antenna which is partially well adapted for the reception of television broadcasts; which is efficient in operation and compact in form; and may be readily and economically produced commercially.

Hence, while I have illustrated and described the preferred embodiments of my invention, it is to be understood that these are capable of variation and modification, and I therefore do not wish to be limited to the precise details set forth, but desire to avail myself of such changes and alterations as fall within purview of the following claims.

60 I claim:

1. An antenna comprising dielectric supporting means, four elongated substantially straight bars, each of said bars having an inner end portion and outer end portion and being disposed in spaced relation to each other with said inner end portion mounted on said supporting means and said outer end portion projecting outwardly from said supporting means, said bars projecting from said supporting means in two substantially oppositely projecting pairs, each of said pairs comprising an upper bar and a lower bar disposed in vertically spaced substantially parallel relation to each other, two substantially U-shaped bars, each of said U-shaped bars having two elongated legs and being slidably mounted

on a respective one of said pairs of bars in outwardly projecting relation thereto and with each of said legs mounted on a respective bar of said pair for movement longitudinally thereof, two other elongated bars substantially straight throughout their length, each of said other bars having an inner end portion and an outer end portion and being disposed in spaced relation to the other of said other bars and said four bars with said inner end portion mounted on said supporting means and said outer end portion projecting outwardly from said supporting means, each of said two other bars being disposed between said upper and lower bars in a respective one of said pairs and being disposed at a horizontal acute angle to said respective pair, means selectively electrically connecting said inner end portion of each of said two other bars to said inner end portion of only one of said bars in said respective pair, and electric lead wires selectively connected to said inner end portions of only the other of said bars in each of said pairs and projecting therefrom.

2. An antenna as defined in claim 1 and which includes conductor means directly interconnecting said outer end portions of said other bars.

3. An antenna comprising dielectric supporting means, four elongated substantially straight bars, each of said bars having an inner end portion and outer end portion and being disposed in spaced relation to each other with said inner end portion mounted on said supporting means and said outer end portion projecting outwardly from said supporting means, said bars projecting from said supporting means in two substantially oppositely projecting pairs, each of said pairs comprising an upper bar and a lower bar disposed in vertically spaced substantially parallel relation to each other, two substantially U-shaped bars, each of said U-shaped bars having two elongated legs and being slidably mounted on a respective one of said pairs of bars in outwardly projecting relation thereto and with each of said legs mounted on a respective bar of said pair for movement longitudinally thereof, two other elongated bars substantially straight throughout their length, each of said other bars having an inner end portion and an outer end portion and being disposed in spaced relation to the other of said other bars and said four bars with said inner end portion mounted on said supporting means and said outer end portion projecting outwardly from said supporting means, each of said two other bars being disposed between said upper and lower bars in a respective one of said pairs and being disposed at a horizontal acute angle to a respective one of said pairs, means selectively electrically connecting said inner end portion of each of said two other bars to said inner end portion of only one of said bars in said respective pair, and electric lead wires connected to the inner end portion of said first mentioned bars.

4. An antenna as defined in claim 3 and in which the acute angle at which each of said other bars is disposed relative to said respective one of said pairs is not substantially less than ten degrees and not substantially more than thirty degrees.

5. An antenna comprising dielectric supporting means, four elongated substantially straight bars, each of said bars having an inner end portion and outer end portion and being disposed in spaced relation to each other with said inner end portion mounted on said supporting means

and said outer end portion projecting outwardly from said supporting means, said bars projecting from said supporting means in two substantially oppositely projecting pairs, each of said pairs comprising an upper bar and a lower bar disposed in vertically spaced substantially parallel relation to each other, two slides, each of said slides extending between and electrically interconnecting the bars in a respective one of said pairs and being movable longitudinally thereof, two other elongated bars having inner end portions and outer end portions, said other bars being mounted at their inner end portions on said supporting means in spaced relation to each other and having their outer end portions projecting horizontally away from said first mentioned bars, electrical conductor means selectively connecting the inner end portion of each of said other bars to the inner end portion of a respective one of said bars in a respective one of said pairs, other electrical conductor means mounted on and directly interconnecting said outer end portions of said two other bars, and means connected to said first mentioned bars for connecting the latter to a receiver.

6. An antenna as defined in claim 5 and in which said other electrical conductor means comprises an elongated conductor consisting of material of substantially smaller cross-sectional area than said other bars.

7. An antenna as defined in claim 5 and in which said other electrical conductor means comprises a tension coil spring mounted on and extending in tension between said outer end portions of said other bars.

8. An antenna comprising dielectric supporting means, two reversely bent bars, each bar having two elongated legs disposed in spaced relation to each other at one end to form an open end portion and connected together at the other end to form a closed end portion, said bars being mounted on said supporting means with said open end portions disposed in spaced relation to each other and said closed end portions projecting away from each other, said one end of each leg in each of said pairs being electrically connected to said one end of the other said leg in said pair only through said closed end portion of said pair, two elongated bars having inner end portions mounted on said supporting means in spaced relation to each other and having outer end portions projecting horizontally away from said first mentioned bars, electrical conductor means selectively connecting said inner end portion of each of said elongated bars to said inner end portion of a respective one of said two legs of a respective one of said bent bars, electrical conductor means mounted on and directly interconnecting said outer end portions of said elongated bars, and electrical conductor means connected to said bent bars for connecting the latter to a receiver.
